Patented Oct. 21, 1975

237,244

UPRIGHT VACUUM CLEANER OR SIMILAR ARTICLE

Clyde H. Williams, Coldwater, Mich., assignor to
The Scott & Fetzer Company, Bronson, Mich.

Filed May 28, 1974, Ser. No. 473,755

Term of patent 14 years

Int. Cl. D7—05

U.S. Cl. D7—165

Fig. 1

Fig. 2

FIG. 1 is a perspective view of an upright vacuum cleaner or similar article showing my new design;
 FIG. 2 is a rear elevational view thereof;

FIG. 3 is a side elevation thereof;

FIG. 4 is a top plan view taken along line 4—4 of FIG. 3;

FIG. 5 is a cross-sectional view taken along line 5—5 of FIG. 3;

FIG. 6 is an end elevational view taken along line 6—6 of FIG. 3.

I claim:

The ornamental design for an upright vacuum cleaner or similar article, as shown.
